(57) **CLAIM**

The ornamental design for a brimless cap, as shown and described.

DESCRIPTION

FIG. 1 is a perspective top front right view of a brimless cap, showing my new design;

FIG. 2 is a perspective top rear left view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines indicate boundary regions and form no part of the claimed design.
